East Orange, N. J., a corporation of
New Jersey

Application February 27, 1932, Serial No. 595,625

17 Claims. (Cl. 123—179)

This invention relates to engine starters, and more particularly to the engaging, or meshing, mechanism employed in starters for internal combustion engines.

5 One object of this invention is to provide a starter having a novel power transmission unit in combination with means for engaging and disengaging said unit with respect to a member of an engine to be started.

10 Another object of this invention is to provide a novel transmission assembly in which the starter mechanism is positively and promptly released from operative engagement with the engine when the latter operates under its own power.

15 A further object is to provide a strong, light, yet efficient power transmission unit in a starter of the foregoing character.

The above and further objects and novel features of this invention will more fully appear from the following description taken in connection with the accompanying drawings. It is to be expressly understood, however, that the drawings are for the purposes of illustration only and are not designed as a definition of the limits of 25 the invention, reference being had for this purpose to the appended claims.

In the drawings, wherein like reference characters refer to like parts in the several views,

Fig. 1 is a vertical sectional view of an inertia 30 type starter embodying the present invention;

Fig. 2 is a fragmental similar view showing another embodiment of the invention applied to a starter of the direct cranking type;

Fig. 3 is a transverse sectional view taken along 35 line 3—3 of Fig. 2;

Fig. 4 is a similar view showing a third embodiment; and

Fig. 5 is a partial top plan view taken substantially along the line 5—5 of Figs. 2 and 4.

40 An inertia starter embodying the present invention is illustrated in Fig. 1 as comprising a housing 5 provided with a flange 6 adapted to be bolted to a corresponding flange 7 on the engine casing; the housing 5 being provided with additional flanges to which are bolted or otherwise 45 securely fastened a hand crank housing 8 and a flywheel housing 9. A thin metallic protective hood 10 is provided for the portion of the starter which extends into the crank case of the engine,

50 this hood being secured in place between the flanged portions 6 and 7 above referred to.

The inertia starter, as herein shown by way of example, includes an inertia flywheel 11 which, when rotated at high speed, receives an accumulation 55 of energy for cranking the engine upon

subsequent transfer of such energy thereto. Both power and manual actuating means, referred to hereafter as driving means, are provided for rotating this flywheel and storing energy therein. The manual cranking means preferably comprises 5 a shaft 12 rotatably mounted in the hand crank housing 8 and supported therein as by means of ball and roller bearings 13. The outer end of said shaft projects from the housing and is provided with suitable means such as pins 14 for 10 engagement with an ordinary hand crank. Fixedly secured to the inner end of shaft 12 is a bevel gear 15 which meshes with a second bevel gear 16 that is preferably formed integral with a sleeve 17, said sleeve being rotatably supported by a 15 bearing 18 held in place in the housing section 5 by means of rings 19. A retaining nut 20 threaded to sleeve 17 holds bearings 18 against movement relative to said sleeve.

The inner end of sleeve 17 is milled to form a 20 positive driving connection with a barrel 21 rotatably mounted, as by means of ball bearings 22 and 23 secured in the flanged housing section 6. The closed end of barrel 21 is provided with a flange 24 from which extends preferably three 25 tubular bearing sleeves 25, one of which is shown in section. Each of these sleeves, which are spaced at intervals of 120 degrees around the inner face of flange 24, is placed into a counterbore in said flange and, if desired, may be formed 30 integrally with a bearing retaining ring 26. Screws 27 pass through the sleeves and are threaded into flange 24. Ball bearings 28 are mounted on sleeves 25 and rotatably support the three 35 planetary gears 29, one of which is shown in section. Rigidly secured to the face of the flanged housing member 5 is an annular gear 30 which is adapted to mesh with the planetary gears 29. Each of the latter gears is in mesh with a sun gear 31 which is preferably integral with a spur 40 gear 32 which is rotatably mounted on hub 17, concentric therewith. Preferably, spacing washers 32a are interposed between the gear 32 and a suitable shoulder formed on sleeve 17 to maintain said gear in proper position thereon.

45 Gear 32 preferably engages a pinion 33 rigidly secured to a lay shaft 34 rotatably supported in the housing member 5 through the provision of bearings 35 and 36. Bearing 35 is held against a suitable shoulder on said housing by means of a cap 37 secured to the side of housing 5, while a nut 38, which is threadedly received by the end of lay shaft 34, and a spacing sleeve 39, hold the pinion 33 and the crown gear 40, integral 50

55

therewith, in place with the assistance of a collar 41.

The gear 40 meshes with a pinion 42 rigidly attached to the inner end of a sleeve 43 which is fitted into a counter-bore in the hub 44 of flywheel 11. The flywheel housing section 9 is provided with a boss 45, and positioned in said boss are ball bearings 46 and 47 which rotatably support the hub 44 of flywheel 11, the said hub being suitably secured to sleeve 43. Bolt 48, passing centrally through the flywheel hub 44 and sleeve 43, prevents relative longitudinal movement of these members. Bearings 46 and 47 are securely held in place by a ring 49, ring 50, and an annular abutment 51 integrally formed with sleeve 43; while the bearings 46 and 47 are properly spaced by a spacing sleeve 53 and an inwardly projecting abutment 54.

When it is desired to manually rotate the flywheel to store starting energy therein, rotation of shaft 12 is transmitted through bevel gears 15 and 16, sleeve 17, barrel 21, planetary gears 29, sun gear 31, spur gear 32, pinion 33, crown gear 40, and pinion 42, to the flywheel 11. The energy of the rotating flywheel is imparted by the reduction gear train described above, to barrel 21 and thence, through the novel power transmission assembly to be described, to a starter jaw or driving member 55 that is adapted to mesh with, but is normally out of engagement with, a similar jaw 56 formed on the crankshaft 57, or extension thereof, of the engine to be started.

The present invention provides a novel power transmission unit interposed between the barrel 21 and the crankshaft 57, in combination with means for moving said power transmission unit axially into driving engagement with the crankshaft. In the form shown in Fig. 1, the power transmitting unit comprises, in part, a drum 58 open at one end, and drivably connected as by splines to driving barrel 21, thereby being capable of axial movement relative thereto. Jaw clutch member 55 has a counter-bore of a diameter equal to the inner diameter of drum 58 and is telescopically received by the open end of said drum where the latter's inner diameter is slightly increased for this purpose, thus forming a cylindrical enclosure 59 into which is fitted a torsion spring 60, the latter being inserted under a predetermined initial compression. The drum 58 and the jaw clutch member 55 are prevented from relative axial movement by being rigidly constrained between a shoulder 64 formed on rod 61 which passes centrally through these members, and a nut threadedly received by the end of said rod. The outer surface of spring 60, because of its initial compression, is in frictional cooperation with the inner surfaces of enclosure 59. Thus when there is a tendency to rotate drum 58 in one direction relative to the jaw clutch member 55, the frictional cooperation between the surface of the enclosure 59 and the outer surface of spring 60 tends to unwind said spring and force its outer surface more tightly into engagement with the walls of enclosure 59, thus locking drum 58 and the jaw clutch member 55 together and serving as a driving connection therebetween in that direction, such direction being that in which the unit rotates for starting the engine. When, however, the tendency is for the driving member 55 to become the driver, the frictional relationship between the outer surface of the spring and the enclosure walls tend to wind the spring more tightly, reducing its effective diameter, thus lessening the frictional cooperation

between said spring and the walls of said enclosure means and permitting free relative rotational movement between the drum 58 and the jaw clutch member 55.

Means are provided for shifting the above-described drive unit axially in order to effect a driving engagement between jaw clutch member 55 and the complementary jaw clutch member 56 on the crankshaft or other suitable part of the engine on which the starter is mounted. Such means may, as shown in Fig. 1, include a simple linkage, only part of which is shown, adapted to be either electrically or manually controlled. Rod 61, forming a part of this meshing linkage, has a sliding fit through sleeve 17 and is pivotally connected to link 62 which is in turn rigidly connected to and constrained to turn with a bar 63. The latter may be rocked manually or by electrical means through a suitable linkage external to the starter casing, such as that disclosed fully in my prior Patent No. 1,833,948 of December 1, 1931.

A suitable spring (not shown) is preferably employed in the meshing linkage for the purpose of aiding in demeshing the drive unit and positively maintaining the same normally out of engagement with the crankshaft of the engine, with drum 58 in abutting relation to the shoulder 64 on rod 61, so as to be moved thereby on the next meshing operation.

Describing a manual cycle of operation, the operator rotates the hand crank, and this motion is transmitted through bevel gears 15 and 16, sleeve 17, barrel 21, planetary gears 29, sun gear 31, spur gear 32, pinion 33, gear wheel 40, pinion 42 to the flywheel 11, whereby the latter is rotated. The rotation of the barrel 21 acts through its splined connection to the drum 58 to rotate the latter which in turn acts through the torsion spring 60 to rotate the jaw clutch member 55 on which there is no load and, therefore, no tendency other than that due to the inertia of the jaw clutch 55 toward relative rotation between said jaw and said drum.

When the flywheel is brought up to a sufficiently high speed of rotation, the operator actuates the meshing linkage, thereby moving rod 61 to the left in Fig. 1, and the shoulders on said rod forces the drive unit outwardly and brings the jaw clutch 55 into driving engagement with jaw 56 on the engine crankshaft. Upon engagement of said jaws, there is an immediate tendency to rotate the jaw clutch member 55 and the drum 58 relative to each other. As pointed out above, the spring 60 now tends to unwind, increasing the friction between itself and the walls of the enclosure 59, and thus producing a driving connection between the drum and the engine crankshaft.

When the engine starts, the jaw clutch member 56 rotates faster than when being driven by the starter, and tends to drive the jaw clutch member 55 at an equally increased speed. The inclined teeth of the jaws 55 and 56 now coact to move the power transmission unit to the right in Fig. 1, disengaging the said jaws. This movement of disengagement may also be accomplished by the operator through the meshing linkage and rod 61. It is to be noted that in the event the demeshing of jaws 55 and 56 does not occur automatically at the instant the engine starts, such as would be the case if a square-toothed jaw or a pinion were used, the operator may disengage said jaws manually at the instant of starting. No harm will result, however, if the parts are not demeshed.

immediately since in the event there would be a relative rotation of the drum 58 and jaw 55 such as would wind the spring 60 tighter and permit of free overrunning of the jaw clutch member 55 5 relative to the drum 58.

In the event of a back-fire, there would be the same tendency toward the unwinding of the spring 60 as when starting the engine and, therefore, a 10 tendency for the engine to drive the starter mechanism in the reverse direction to its normal operation. As was pointed out above, however, the 15 spring 60 is installed under such initial compression as to slip at a predetermined load value for protection against any over-load. Therefore, it is readily seen that if the forces set up by the 20 engine back-fire exceed this predetermined load value, which may be set at somewhat less than the maximum capacity of the starting motor, slippage will occur and no damage will be done to the starter parts.

It has been stated that power driving means may be provided for energizing the starter mechanism, and such means, as illustrated in Fig. 1, 25 consists of an electric motor 62 rigidly attached as by means of bolts to the outer face of the flywheel housing 9. For the purpose of automatically connecting and disconnecting the motor 62 and the flywheel 11, shaft 63 of the motor is provided with the usual threaded portion 64 on 30 which is mounted for rotary and longitudinal movement a clutch member 65 adapted to engage a clutch element 66 rigidly attached in any suitable manner to the outer face of the flywheel. When the motor 62 is energized, the inertia of 35 clutch member 65 coacts with the threaded portion 64 of the motor shaft 63 to move said clutch member longitudinally on the shaft into engagement with clutch member 66 whereupon the motor is effective to rotate the flywheel. After the 40 flywheel has been brought up to the proper speed of rotation, the electric circuit to motor 62 may be opened and the tendency of the flywheel to drive the clutch member 65 will cause it to return to its normal position of disengagement.

45 Means are provided for normally maintaining the clutch member 65 out of engagement with clutch member 66, and as herein illustrated, such means consists of the usual coil spring 67 held in place by nut 68 which is threadedly received 50 by the inner end of motor shaft 63. The energy stored in the flywheel 11 by the motor 62 is utilized to crank the engine in the same manner as pointed out in the description of the manual operation of the starter.

55 Automatic means may be provided for moving the power transmission unit into driving engagement with a member of the engine to be started, and two embodiments of such means are shown as in Figs. 2 and 4 applied to direct cranking 60 starters. Referring now to these figures, an electric motor 62 is shown adapted to rotate the barrel 121 through suitable power transmitting mechanism such as a reduction gear train. As shown, the gear train includes a sun gear 131 65 keyed to the armature shaft 163 and adapted to mesh with planetary gears 129 which in turn mesh externally with a stationary internal gear 130 suitably secured to the housing member 105. The planetary gears 129 are mounted on bearing 70 sleeves 125 which are counter-sunk at intervals preferably of 120 degrees into the outer side of the closed end of barrel 121. Screws 127 pass through the sleeves 125 and are threaded into the end of the barrel 121.

75 The barrel 121 is rotatably mounted within

housing member 105 and is prevented from moving axially in one direction by a flange at the closed end thereof which bears against the housing member 105 and in the other direction by split ring 69 which fits into a channel cut into the 5 outer surface of said barrel and which abuts a shoulder on the housing member 105; the power transmitting unit consisting, as in Fig. 1, of drum 158, jaw clutch member 155 and torsion spring 60; the drum being splined to the interior of the 10 barrel 121.

The means for moving the meshing unit into engagement with jaw 156 of the engine on which the device is mounted comprises, as shown in Fig. 3, a three piece ring 70 having a cylindrical 15 flange with a bead 71 on the interior of said flange. The bead 71 is adapted to be received and to frictionally bear against a lip portion on the inner face of the hood 110. A groove is provided on the outer surface of said flange for receiving a 20 toroidal spring 72, Figs. 2 and 3, which maintains the desired frictional relationship between ring 70 and hood 110. Rigidly attached to one sector of the ring 70, as by means of set screws, is a sleeve 73 loosely fitted over the outer end of drum 25 158 and carrying an inwardly projecting pin 74 which has a sliding fit in a helical slot 75 cut into the outer surface of drum 158.

In operation, when the motor switch is closed, 30 rotary motion is transmitted from the motor 62 through shaft 163 and sun gear 131 to planetary gears 129 which not only rotate about their own axes but, by virtue of the fixed internally toothed annular gear 130, they revolve about the sun gear 131, thus rotating the barrel 121. Power 35 is transmitted from said barrel through the splined connection to drum 158 and thence, as has been heretofore described, through the spring 60 to jaw clutch member 155. The ring 70 is, however, retarded by the friction between itself 40 and the housing member 110, whereupon the pin 74 cooperates with helical slot 75 in forcing the meshing unit to the left and into engagement with jaw 156 on the crankshaft 157. When complete meshing of the jaws is effected, the ring 70 45 and the sleeve 73 are constrained to rotate with the power transmitting unit irrespective of the friction between ring 70 and the housing member 110, such friction being only enough to hold the ring against rotation while the jaws are moved 50 into engagement. When the engine starts, disengagement is effected by the interaction of the inclined faces of jaws 155 and 156 as described above.

Mechanism involving the same principle as that 55 shown in Fig. 2 is illustrated in Fig. 4, wherein a ring 76 is frictionally held between the inner surface of hood 110 and a resilient spring plate 77 suitably secured to the housing member 105. Rigidly secured to the ring 76 is a pin 174 similar 60 in purpose to pin 74 of Fig. 2, which is slidably received in the slot 75 of the drum 158. The operation of this embodiment is substantially the same as that of the disclosure in Fig. 2.

There is thus provided a novel combination of 65 power transmitting device including a clutching member capable of overrunning in one direction and yielding at a predetermined over-load in the other direction, with means cooperating with said device for moving the latter into driving engagement with a member to be driven. There is provided also a relatively simple, readily constructed and assembled device which not only serves as a power transmitting unit and an over-load safety release but also one which incorporates means for 70 75

effecting a smooth, easy engagement between the driving and driven members.

While there has been shown and described only certain embodiments of the invention, it is to be expressly understood that the same is not limited thereto. Various mechanical changes may be made in the details of construction of this invention without departing from the spirit thereof. Reference will therefore be had to the appended claims for a definition of the limits of the invention.

What is claimed is:

1. In apparatus of the class described, the combination of a drum mounted for both rotary and axial movement, a starter member adapted to drivably engage an engine member and mounted for longitudinal movement with said drum but capable of rotary movement relative thereto, means for transferring cranking torque from said drum to said starter member, relatively stationary frictional means distinct from said torque transmitting means but cooperating with said drum for effecting axial movement thereof, and means for causing said relatively stationary means to rotate with said drum as soon as said axial movement has been completed.

2. In a starter of the type wherein energy is transmitted by means of reduction gearing, the combination with said gearing of a power transmitting unit including a rotatably and axially movable drum, a starter member adapted to drivably engage an engine member, a torsion spring for drivably connecting said drum to said starter member, and means comprising a helical slot on the outer periphery of said drum, a pin engaging said helical slot, and frictional means for retarding the rotation of said pin for moving said power transmitting unit into effective driving engagement with said engine member.

3. In apparatus of the class described, an axially movable member adapted to be rotatably driven, a member adapted to engage a part of an engine to be started, means for drivably connecting said members when there is a tendency to relative rotation in one direction while permitting free relative rotation therebetween in the reverse direction, means for locking said members against relative axial movement, relatively stationary frictional means distinct from said connecting means but cooperating with said first named member in moving said member axially, and means for causing said relatively stationary means to rotate as soon as said axial movement has been completed.

4. In a starter for an internal combustion engine, driving means, power transmitting means interposed between said driving means and a member of said engine, said power transmitting means including a unit comprising two members cooperating to form a cylindrical enclosure and a coil spring in said enclosure adapted to transmit torque between said two members up to a predetermined load, means for drivably engaging one of said members with a member of said engine, relatively stationary frictional means distinct from said torque transmitting means but cooperating with said cylindrical unit in moving it into driving engagement with said engine member, and means for causing said relatively stationary means to rotate as soon as said engaging movement has been completed.

5. In an engine starter, a power transmitting unit including a torsion spring clutch, means for rotating said unit, reduction gearing interposed between said last named means and said unit,

means for moving said unit axially, such means including a relatively stationary friction member disposed outside the path of power transmission but adapted to coact with said unit upon the rotation of the latter, and means for causing said relatively stationary member to rotate with said unit as soon as said axial movement has been completed.

6. In combination, a power transmitting unit comprising two telescoping members, and a torsion spring frictionally engaging each of said members and adapted to transmit power from one to the other of said members, means for driving one of said members, a helical slot in said last named member, the other of said members being adapted to drivably engage a member to be driven, and means for moving said power transmitting unit axially, said latter named means comprising a rotatable friction element adapted to frictionally engage a stationary member, a pin rigidly attached to said friction member, said pin projecting into said helical slot for moving said power transmitting unit axially during relative rotation between said frictional element and said power transmitting unit.

7. In apparatus of the class described, the combination with a power transmitting unit, including an overrunning clutch, of means for moving said power transmitting unit axially, said means comprising a rotatable friction element, resilient means for maintaining said friction element in frictional engagement with a stationary part; a pin distinct from said power transmitting unit, but adapted to coact with said power transmitting unit for moving said unit into engagement with a member of an engine to be started.

8. In an inertia starter wherein a jaw clutch member is adapted to engage and drive, a complementary jaw clutch member on an engine shaft, the combination with said first named jaw clutch member of means including a torsion spring clutch for transmitting energy to said first named jaw clutch member, relatively stationary frictional means distinct from said energy transmitting means but cooperating with said first named jaw clutch member for effecting engaging movement thereof, and means for rotating said relatively stationary means as soon as the engaging movement has been effected.

9. In a starter of the class described, the combination of a rotatable drum, a jaw clutch member, means including a torsion spring clutch for transmitting cranking energy from said drum to said jaw clutch member, means including a relatively stationary friction element distinct from said energy transmitting means for effecting the engagement of said jaw clutch member with a complementary jaw clutch member, on an engine shaft, and means for rotating said relatively stationary element as soon as the jaw clutch members have been engaged.

10. In apparatus of the class described, the combination of a power transmitting unit including a torsion spring clutch, means including a relatively stationary friction element distinct from said power transmitting unit but adapted to coact with said power transmitting unit for moving the latter into drivable engagement with a member of an engine to be started, and means for rotating said relatively stationary element after said engagement has been effected.

11. In a starter of the class described, the combination of a driven member, a driving member in which energy may be developed for transmis-

- sion to a member of the engine to be started, means including a two-part friction clutch for drivably connecting said driving member with said driven member, and means for meshing said driven member with said engine member, said meshing means including a rod extending through the two parts of said friction clutch to hold said parts against any substantial relative axial movement.
- 5 12. In a starter of the class described, the combination of a driven member, a driving member in which energy may be developed for transmission to a member of the engine to be started, means including a torsion spring clutch for drivably connecting said driving member with said driven member, and means for meshing said driven member with said engine member, said meshing means including a part serving to hold the parts of said clutch against relative axial movement.
- 10 13. In a starter of the class described, the combination of a driven member, a driving member in which energy may be prepared for transmission to a member of the engine to be started, means including a torsion spring clutch for drivably connecting said power member with said driven member, and means for meshing said driven member with said engine member, said meshing means including a rod extending through the parts of said friction clutch to hold said parts against relative axial movement.
- 15 14. In a starter of the class described, the combination of a driven member, a power member from which energy may be taken for transmission to a member of the engine to be started,
- a torsion spring clutch for drivably connecting said driving member with said driven member, means for energizing said driving member, and means distinct from said energizing means for meshing said driven member with said engine member, said last named means including a member engaging said driving member to first restrain rotation thereof and thereafter rotate therewith.
- 20 15. In a starter of the class described, the combination of a driven member, a power member from which energy may be taken for transmission to a member of the engine to be started, a torsion spring clutch for drivably connecting said power member with said driven member, and means operable independently of said power member to mesh said driven member with said engine member, said last named means including a member engaging said driving member to first restrain rotation thereof and thereafter rotate therewith.
- 25 16. In a clutch of the class described, the combination with a pair of nested flat-ended cups having cylindrical inner and outer surfaces, and a third cup driven thereby, of means engageable with the inner surface of the inner nested cup to transmit torque to the driven cup, and means drivably connecting said nested cups.
- 30 17. In a clutch of the class described, the combination with a pair of nested driving cups, and a third cup driven thereby, of means engageable with the inner surface of the inner nested cup to transmit torque to the driven cup, and means drivably connecting said nested cups.

RAYMOND P. LANSING. 35
